RECIPROCATORY PLUNGER TYPE
RATCHET WRENCH

William F. Ludwig, Parma, Ohio

Application January 18, 1952, Serial No. 267,057

2 Claims. (Cl. 81—61)

1

The present invention relates to improvements in a reciprocatory plunger type ratchet wrench and has for an object the provision of an improved device of this kind which is especially adapted for starting screws and nuts in the direction of their tightened positions in places where it is hard or impossible to reach by hand or with conventional tools.

Another object of the present invention is to provide an improved wrench which is capable of being used to tighten nuts, screws or the like by reciprocating the wrench without removing it from the head of the nut or screws.

A further object of the present invention is to provide an improved structure in which the nut holder and ratchet are made integral and are detachably mounted on the body portion of the wrench so that nut holders of various sizes and shapes may be selectively mounted on the body of the wrench and in the event the teeth of the ratchet become worn or broken a new holder and ratchet unit may be substituted for the old one.

The present invention aims to provide an improved wrench of this character which comprises relatively few parts, is economical to manufacture, has a minimum of working parts and is compact.

With the foregoing and other objects in view, the invention will be hereinafter more fully described and more particularly pointed out in the appended claims.

In the drawings, in which the same parts are denoted by the same reference numerals throughout the several views,

Figure 1 is a perspective view of an improved wrench constructed in accordance with the present invention.

Figure 2 is an exploded perspective view of the body and the plunger shaft of the improved wrench.

Figure 3 is a longitudinal sectional view taken on the line 3—3 of Figure 1, and

Figure 4 is a sectional view taken on the line 4—4 of Figure 1.

Referring more particularly to the drawings, 10 indicates the main body portion of the wrench which may be substantially T-shaped, the arms 11 of which may be formed integral with the body 10 or may be secured to one end thereof as by welding or the like. The opposite end portion of the body 10 may be of slightly greater width than the major portion of the body and is provided with an opening 12.

A combined nut holder and ratchet member, 55

generally indicated at 13, is adapted to be detachably mounted on the enlarged end portion of the body 10 and comprises a cup shaped nut holder 14 and ratchet teeth 15. The nut holder 14 may be of any desired size or configuration for receiving the head 16 of a screw 17 or the like. In the present illustration the cup shaped nut holder 14 is hexagonal in shape so as to accommodate the similarly shaped head 16 of the screw 17. The ratchet teeth 15 are formed on the outer face of the cup shaped nut holder 14 adjacent the closed end 18 thereof and may be formed integrally therewith or fixed thereto in any suitable manner. The closed end 18 of the nut holder 14 has an opening 19 therethrough which is adapted to be brought into registry with the opening 12 of the body 10 when the member 13 is mounted on the body 10.

A bolt 20 extends through the aligned openings 12 and 19 and its threaded end portion 21 extends beyond the body 10 to receive a friction washer 22 and a nut 23 which when screwed home will bind the washer 22 between itself and the body 10 and will draw the head 23 of the bolt 20 against the inner face of the bottom 18 of the nut holder 14. The head 23 of the bolt 20 may be provided with a kerf 24 for receiving a screw driver or the like for facilitating the tightening of the bolt 20 and the nut 23.

A combined plunger shaft and pawl member, 30 generally indicated at 25, comprises an intermediate shank 26, guide stem 27 and a pawl 28. The guide stem 27 is provided by reducing the width of one end portion of the member 25 which will form shoulders 29. The guide stem 27 is adapted to be slidably received by a slot 30 which is formed in a guide 31 carried by the intermediate portion of the arms 11. The guide 31 extends from the upper edge of the arms 11 towards the body 10 and extends therebeyond. 40 The shank 26 is provided with an elongated slot 32 which has a sliding engagement with a guide stud 33 which is threadedly received by an opening 34 in the body 10.

A thumb knob 35 is mounted on the free end portion of the stem 27 and its upper surface may be concave to afford a purchase for the thumb of the user of the wrench. A coil spring 36 encircles the guide stem 27 and has its opposite ends abutting the guide 31 and the knob 35 for normally urging the pawl 28 in a direction away from the ratchet teeth 15. A flat spring 37 has one end portion frictionally held by the fingers 38, 39 and 40 which may be formed integrally with or fixed in any suitable manner on one edge of the body portion 10. The end fingers

38 and 40 are in substantial alignment longitudinally of the body 10 and the intermediate finger 39 is inwardly laterally offset from the fingers 38 and 40.

The end portion of the spring 37 which is retained by the fingers has its inner face engaging the outer face of the intermediate finger 39 and its outer face engaging the inner faces of the end fingers 38 and 40. This arrangement is sufficient so that the spring 37 will be frictionally held in position by the fingers, but, if desirable, the spring may be secured to the fingers by welding or in any other suitable manner.

The edge portion of the shank 26 adjacent the fingers 38, 39 and 40 is cut away to accommodate the fingers and the spring 37 and the free end portion of the spring 37 bears against the edge of the cut away portion of the shank 26 adjacent the pawl 28 for urging the nose of the pawl into firm engagement with the teeth of the ratchet. A substantially U-shaped retaining member 41 has its side 42 secured to the outer face of the body 10 opposite to the cut away portion of the shank 26. The connecting portion 43 of the member 41 extends across the edges of the body 10 and shank 26 opposite to the fingers and the other side 44 of the member 41 overlies and is spaced from the inner face of the body 10 and engages the shank 26 adjacent the pawl 28.

In the operation of the device the proper sized and shaped member 13 is secured to the body portion 10 by bolt 20 and nut 23. The head 16 of the screw 17 will now be inserted in the nut holder 14 and the screw may be brought into registry with the threaded opening of the machine into which it is desired to insert the screw. This may be accomplished regardless of the location of the screw opening since the body 10 and the shank 26 are relatively narrow and elongated. The operator will place his thumb on the concave surface of the knob 35 and his first two fingers in engagement with the arms 11 on the edges thereof remote from the knob 35. By pressing on the knob with his thumb the member 25 will be moved longitudinally of the member 10 against the action of the coil spring 36 so that the pawl 28 which is in engagement with one of the teeth 15 will cause the nut holder 14 to rotate one step in a direction which will cause tightening movement of the screw 17.

The movement of the member 25 under the pressure of the thumb will be limited by the end of the slot 32 which is adjacent the knob 35 engaging the stud 33. Lateral shifting of the shank 26 so that the pawl 28 may clear the next tooth 15 of the ratchet is permitted since the shank 26 is cut away at a point opposite to the retaining member 41. There is sufficient loose play between the slot 30 and the guide stem 27 and the slot 32 and stud 33 so that the shank 26 can pivot about the stud 33 during the lateral shifting of the shank. Upon release of the thumb from the knob 35 the spring 36 will return the member 25 to its original position. The shoulders 29 will engage the inner face of the guide 31 and the end wall of the slot 32 remote from the shoulders 29 will abut the stud 33 and restrict the movement of the member 25 under the influence of the spring 36. The parts will then be in position for another partial rotation of the nut holder 14 by the pawl 28. The member 25 will be guided in its movement by the guide 31 and the retaining member 41 and the flat spring 37 will constantly urge the nose of the pawl 28 into firm engagement with the teeth of the ratchet 15. By

repeating the movement of the member 25 the screw 17 may be easily screwed down tight.

It will also be noted that the device may be used in the form of a ratchet wrench for tightening screw 17 or the like without removing the nut holder 14 from the head 16 of the screw. During this operation the friction washer 22 and the pawl 28 will cooperate to prevent relative movement between the member 13 and the body 10 so that the swinging movement imparted to the body 10 by the operator will be communicated to the nut holder 14 and hence to the screw 17, during the tightening movement of the wrench. In other words, the entire wrench is swung by the hand of the operator about the longitudinal axis of the screw during the tightening movement of the device and on the non-tightening return stroke the pawl 28 is free to click over the ratchet teeth 15 so that the body 10 and plunger shaft 25 will swing about the longitudinal axis of the screw 17 and move with respect to the nut holder 14 to their original positions.

On the return or non-working swinging movement of the body 10 the resistance of the screw to being unscrewed will overcome the frictional resistance of the washer 22 and the pawl 28 will ride over the teeth of the ratchet 15 so that the body 10 may be moved relative to the nut holder 14.

This wrench is adapted to be used on nuts, screws and the like on any kind of machinery and is especially adaptable for use on typewriters and adding machines.

It is obvious that various changes and modifications may be made in the details of construction and design of the above specifically described embodiment of this invention without departing from the spirit thereof, such changes and modifications being restricted only by the scope of the following claims.

What I claim is:

1. A wrench comprising a body portion, an integral nut holder and ratchet detachably and rotatably mounted on said body portion, an integral plunger shaft and pawl member mounted for longitudinal reciprocating and lateral sliding movement on said body portion and comprising a pawl engaging said ratchet and a shank, guide means for guiding said plunger shaft, a plurality of fingers on said body portion adjacent said pawl, and resilient means held by said fingers and bearing against said pawl to urge the pawl into firm engagement with said ratchet, said guide means having a portion engaging said shank to prevent separation of the shank and body portion and to prevent escape of the pawl from the ratchet.

2. A wrench comprising a body portion, an integral nut holder and ratchet detachably and rotatably mounted on said body portion, an integral plunger shaft and pawl member mounted for longitudinal reciprocating and lateral sliding movement on said body portion and comprising a pawl engaging said ratchet and a shank, longitudinally spaced apart guides on said body portion for supporting and guiding said plunger shaft, a guide stem at one end of said plunger shaft of less width than said shank to provide shoulders on said shank, one of said guides having a slot for slidably receiving therethrough said stem, a thumb knob on the free end of said stem for receiving the thumb of an operator for moving said plunger shaft to cause the pawl to rotate the ratchet and nut holder, a coil spring embracing said stem and confined between said knob and the slotted guide for returning said plunger

shaft to its initial position after being moved by the use of the thumb knob, said shoulders engaging said slotted guide to limit the return movement of said plunger shaft under the influence of said spring, a plurality of fingers on said body portion adjacent the other of said guides and said pawl, and a flat spring having one end portion frictionally held by said fingers and its opposite end portion bearing against said pawl to urge the pawl into firm engagement with said ratchet, said other guide having a portion engaging said shank to prevent separation of the shank and body portion and to prevent escape of the pawl from the ratchet.
